Application January 12, 1934, Serial No. 706,444
In Great Britain February 2, 1933

13 Claims. (Cl. 112—38)

This invention is concerned with improvements in or relating to sewing machines and is particularly, but by no means exclusively, concerned with sewing machines suitable for operating on thick stubborn materials such as leather.

In co-pending application of Joseph Gouldbourn, Frank B. Keall and Thomas A. Kestell Serial No. 688,480 filed September 7, 1933, there 10 is disclosed a machine for sewing the outsoles of welted boots or shoes to their welts by a lock-stitch seam, which machine has thread handling and work feeding instrumentalities arranged to enable the machine to operate smoothly at a 15 relatively high speed.

While such a machine as is last referred to has been found to effect very good stitching at relatively high speeds we have found it possible still further to improve the efficiency of the 20 stitching operation of the machine by modifying the action of certain of the thread handling instrumentalities.

In a machine arranged as disclosed in the prior specification above referred to a rotary 25 shuttle of the type disclosed in the co-pending application of Joseph Gouldbourn and Thomas A. Kestell Serial No. 630,044 filed August 23, 1932 upon which Patent No. 1,991,456 issued February 19, 1935 is used and although such a 30 shuttle is found to operate satisfactorily in looping the needle thread over the shuttle thread it is found, when using such a shuttle, that uniform results in the setting of the stitch locks formed between the needle and shuttle threads within 35 the work may not in some circumstances always be obtained.

Such a shuttle as is above referred to has a 40 nose projecting downwardly from the bobbin case and the thread is arranged to pass out of the bobbin case through a hole in the end of the nose. The bobbin case is allowed to vibrate somewhat about the axis of the bobbin during the running of the machine to allow forward 45 limbs of the loops of needle thread lifted over the shuttle to pass between the forward side of the bobbin case and a relatively fixed ridge which engages loosely in a V-shaped groove formed in the front wall of the bobbin case. The said vibration of the bobbin case is effected 50 by the friction between the bobbin case and the rotating shuttle case, and by the action of the forward limb of the loop of needle thread in passing between the said fixed ridge and the sides of the V-shaped groove in the bobbin case. 55 The vibration of the bobbin case is found to

vary in extent during different cycles of the machine and therefore imparts an oscillating movement of inconstant amount to the said nose which, as it moves to and fro, causes small and inconstant amounts of thread to be drawn off the bobbin in successive machine cycles, which inconstant amounts are used up in the formation of successive stitches. 5

Furthermore, since the movements of the said nose are only controlled in a non-positive manner, it is liable to happen during the actual setting of successive stitch locks within the work that the nose, during the setting of one stitch lock, may be rising away from the work and therefore exerting a tension on the shuttle 10 thread and pulling additional thread off the bobbin and, during the setting of the next stitch lock, may descend towards the work and relieve somewhat the tension on the shuttle thread and pay out additional shuttle thread. Therefore, 15 there is a tendency for the actual lengths of thread extending from the nose to the work during the setting of successive stitch locks to vary and also for the tensions in the shuttle thread 20 to vary at these times. 25

We have found that relatively slight variations in the slackness or tautness of the shuttle 30 thread during successive stitch-setting operations causes relatively great differences in the depths to which the successive stitch-locks can 35 be set within the work by a uniform tension exerted on the needle thread. It is one of the objects of the present invention to avoid or at least minimize variations in the slackness or tautness of the shuttle thread during successive 40 stitch-setting operations. The action of drawing the shuttle thread on to the work by the loop of needle thread after the latter has passed over the shuttle, acting as it does in the machine disclosed in the prior specification first mentioned against the action of a tension device 45 on the bobbin case, imposes an appreciable strain on the needle thread and causes substantial reeving of the two threads round each other which is likely to weaken the threads and 50 mar the appearance of the threads in the finished stitch.

In a particular illustrative embodiment of the present invention hereinafter described, the tendency for the threads to reeve around each other 55 as the shuttle thread is being drawn down on to the work by the needle thread is minimized by arranging the bobbin case in the shuttle in such a manner that as the needle thread acts to draw the shuttle thread against the work, the bobbin 55

will approach bodily towards the work and will provide a slackness, of constant amount, in the thread extending from the bobbin to the work. Thus, when the needle thread acts to draw the slackened shuttle thread down on to the work it will be able to lay the shuttle thread easily against the work without causing excessive reeving between the threads since during at least part of the time when the shuttle thread is being laid against the work the movement of the shuttle thread towards the work will not be restrained by the tension device on the bobbin case.

In the machine disclosed in the prior specification first mentioned upper and lower thread locking devices are used which operate alternately to grip the needle thread between the thread supply and a thread measuring device and between the thread measuring device and the looper respectively at certain times in the machine cycle. These devices are so operated in that machine that almost as soon as one of them has gripped the thread, the other disengages the thread so that only one of the two devices is in gripping engagement with the thread at substantially all times. While thread locking devices operated in this manner have hitherto been accepted as satisfactory, there nevertheless arises a danger, particularly when a machine incorporating such devices is run at relatively high speed, that owing to the rapidity with which the needle thread is handled by the various instrumentalities of the machine, thread may steal through that one of the two thread locking devices which is gripping the thread at a particular time or through both locking devices at the time when one is coming into gripping engagement with the thread.

It is a further object of the present invention so to arrange and actuate upper and lower thread locking devices arranged respectively between the supply of needle thread and the thread measuring device and between the measuring device and the stitch forming instrumentalities that both locking devices are in gripping engagement with the needle thread simultaneously throughout substantial portions of a cycle of the machine, thus giving a more positive control of the thread. In the illustrative embodiment of the present invention hereinafter described this result is achieved by providing independent trains of mechanism for actuating each device separately and by actuating these trains of mechanism at such times that both devices remain in gripping engagement with the thread throughout substantial portions of each machine cycle.

In order that the nature of the present invention may be more fully understood, the illustrative embodiment aforementioned will now be described.

Figure 1 is a vertical sectional view illustrating the construction and relative arrangement of some of the principal parts of a machine embodying the several features of the present invention; Figure 2 is a sectional plan view of the machine illustrating particularly the shuttle driving mechanism; Figure 3 is an end view showing certain details of the shuttle driving mechanism; Figure 4 is a front elevation, partly in section, of thread locking means according to the present invention; Figure 5 is a left-hand side elevation, partly in section, of part of the locking mechanism shown in Figure 4; Figure 6 is a front elevation of a shuttle arrangement according to the present invention and thread handling devices of an outsole stitching machine in the relative positions they occupy just after the loop of needle thread

has been drawn away from the shuttle; Figure 7 is a view similar to Figure 6 but with the parts in the relative position they occupy when the loop of needle thread has been drawn down to the work; Figure 8 is a sectional elevation of shuttle driving mechanism according to the present invention; Figure 9 is a plan view partly in section of some of the parts shown in Figure 8; Figures 10 and 11 are detail views of parts shown in Figures 8 and 9; and Figures 12 to 23 inclusive are diagrammatic views illustrating the successive positions taken by the shuttle, take-up, thread locks and pull-off during the formation of a stitch.

The illustrative embodiment will be considered as comprising an outsole stitching machine which, except in so far as is hereinafter indicated, has thread handling instrumentalities and other cooperating members substantially identical with and arranged to operate in the same manner as those of the machine disclosed in the 20 specification of application No. 688,480.

The shuttle case 1 of the illustrative embodiment, while being of the same general construction as the shuttle case of the machine disclosed in application Serial No. 630,044 has a bobbin 25 case 3 mounted in it of somewhat different construction. The bobbin case 3 (and therefore the bobbin which it contains) is also mounted in the shuttle case in a somewhat different manner from that of the bobbin case described in the 30 specification of Patent No. 1,991,456.

The bobbin case 3 of the illustrative embodiment is held from complete rotation with the shuttle case by a fixed ridge engaging loosely in a V-shaped groove in the front wall of the bobbin 35 case in the manner described in the specification of Patent No. 1,991,456 and has a counterpart 5 to the nose referred to as 87 in that specification but the exit hole 7 for the shuttle thread from which the latter passes directly to the work is, in the illustrative embodiment, formed in the bobbin case 40 3 close against the root of the nose 5 and close against the outer face of the side wall of the bobbin case instead of being formed in the free end of the nose as described in Patent No. 1,991,456. 45 Thus the exit hole 7 in the front wall of the bobbin case for the shuttle thread is, in the present illustrative embodiment spaced only about half way between the axis of the bobbin case and the free end of the nose. Thus, as the bobbin case 50 50 vibrates to and fro during the running of the machine, the amount of thread pulled off from the bobbin due to the oscillations of the thread exit hole in the present illustrative embodiment are substantially less than the amounts pulled off by 55 the oscillations of the thread exit hole when the latter is formed in the end of the nose, as described in Patent No. 1,991,456, and thus the variations in the slackness or tautness of the shuttle thread during the setting of successive stitch 60 locks in the present illustrative embodiment will be substantially less than occur when a bobbin case of the type disclosed in the application last referred to is used, thus tending to make for greater uniformity in the setting of successive 65 stitch locks.

Although the bobbin case of the present illustrative embodiment has a nose 5 similar to that disclosed in Patent No. 1,991,456, this nose serves purely to prevent the shuttle thread, if for any 70 reason it should become unduly slack, from bending so far rearwardly as to become liable to be caught by the beak 9 of the rotating shuttle. It will be understood that, as in the case of the shuttle referred to as being described in Patent 75

No. 1,991,456, the thread passes outwardly from the bobbin, through a hole in the side wall of the bobbin case and around the outside of the wall to the exit hole 7 in the nose which is close to the side wall of the bobbin case, the thread, as it passes between the hole in the side wall of the bobbin case and the exit hole, passing through an adjustable tension device arranged on the outside of the side wall of the bobbin case.

10 The said thread exit hole 7 is so positioned on the bobbin case that it lies close to the lowest point on the bobbin case and substantially on a line drawn from the centre of the shuttle case to the needle hole in the work into which a stitch lock formed between the needle and shuttle threads is being drawn by the tension on the needle thread during the setting of a stitch.

In the shuttle disclosed in Patent No. 1,991,456, the bobbin case is mounted in the shuttle case 1 in a housing which is concentric about the axis of the shuttle case but in the shuttle of the illustrative embodiment now being described the bobbin case 3 is mounted in the shuttle case 1 in a housing which is eccentric about the axis of the shuttle case. For this purpose the pin secured to the shuttle case is offset about three thirty-seconds of an inch from the axis of rotation of the shuttle case, the axis of the said pin lying on a line drawn from the axis of rotation of the shuttle case 1 to the forward end of the beak 9 of the shuttle and between the axis of rotation of the shuttle case and the shuttle beak as indicated by the dot-and-dash lines in Figures 6 and 7. The bobbin is supported on a stem in the bobbin case concentrically with the latter.

By arranging the bobbin case 3 eccentrically in the shuttle case 1 and by arranging the supporting pin for the bobbin case to be offset from the axis of the shuttle case along the particular direction above mentioned, certain desirable results hereinafter specified are achieved during the formation and setting of a stitch, as will be apparent from an inspection of Figures 6 and 7 and Figures 12 to 23. The shuttle case 1 of the illustrated machine is given two complete rotations at a varying speed during each stitch forming cycle, the connections for driving the shuttle (see Figs. 2 and 3) comprising offset shafts 10 and 12, cranks 14 and 16 on the shafts and a connecting link 18. 50 The shuttle case is so arranged in the machine that as the setting of a stitch is being completed the beak 9 of the shuttle has passed through the lowest point in its path and is commencing to rise, the thread extending at this time from the exit hole 7 in the bobbin case 3 to the work, lying substantially in a plane which extends from the needle hole in the work, into which the shuttle thread is being drawn by the needle thread, through the axis of rotation of the shuttle case and also through the end of the shuttle beak and the axis of the pin which carries the bobbin case.

When the setting of the stitch has been substantially completed continued rotation of the shuttle case 1, acting through the eccentric pin carrying the bobbin case 3, causes the bobbin case to lift bodily and the stitch having been more or less completely set and, the needle thread still being under tension and therefore assisting in preventing the thread lock from being drawn upwardly out of the needle hole, causes a certain amount of thread to be drawn off the bobbin. When the shuttle case has rotated through one hundred and eighty degrees from the position last mentioned, the lifting of the bobbin case will, 70 since it is offset three thirty-seconds of an inch

from the axis of the shuttle case, have caused some three sixteenths of an inch of thread to be pulled off the bobbin against the action of the tension device on the bobbin case. As the beak of the shuttle case descends once more towards its lowest position, the bobbin case will descend towards the work and will pay out into the length of shuttle thread extending between the bobbin and the work the three sixteenths of an inch of thread which was drawn off the bobbin after the 10 completion of the previous stitch setting operation. The thread drawing-off and paying out movements of the bobbin case just above mentioned will take place during the first half of each stitch forming cycle of the machine but as, 15 after the completion of the setting of the previous stitch, no drawing down on to the work of the shuttle thread by the needle thread takes place until during the second half of a stitch forming cycle (during which second half the 20 shuttle makes a further complete rotation) the paying out of the said portion of shuttle thread during the first half of the cycle is idle. -

As the shuttle rotates once more during the second half of the machine cycle, the shuttle 25 beak 9 engages the loop of needle thread, held open for it by the needle 11 and thread lifter 13, and rises to lift the said loop over the shuttle. As the shuttle beak rises, the bobbin case 3 also rises bodily (due to its eccentric mounting in the 30 shuttle case) and draws taut the slackened thread passing from the shuttle to the work. When the loop of needle thread has been lifted over the highest part of the shuttle, the continued rotation of the shuttle causes the shuttle beak 35 to commence to descend towards the work and causes the bobbin case 3 likewise to commence to descend towards the work. As the shuttle beak and bobbin case descend in unison towards the work, the loop of needle thread will be drawn 40 down towards the work over the shuttle, and round the thread issuing therefrom, by the rotary take-up device of the machine, which take-up device is the same in construction, arrangement, and operation as the take-up device disclosed in 45 application Serial No. 683,480, and the bobbin case will once more be rapidly paying out towards the work the amount of thread drawn off from the bobbin during the first half of the machine cycle. Thus the nearer the shuttle beak approaches towards its lowest position and the further the loop of needle thread is drawn down over the shuttle, the more slack will the shuttle thread extending down to the work become. The 50 loop of needle thread is actually pulled off the shuttle by the rotary take-up device, some eighty to ninety degrees in the rotation of the shuttle before the shuttle beak again reaches the position it occupies when the next stitch setting operation is completed and when the loop of needle thread is pulled off the shuttle and into contact with the shuttle thread, which it straddles, the descending bobbin case will already have paid off about half of the amount of thread pulled off the bobbin at the conclusion of the previous 55 stitch forming cycle. The shuttle thread will therefore already be in a slackened condition when it is engaged by the loop of needle thread and the latter can therefore commence to pull it towards the work without causing any appreciable reeving of the two threads together and without having to overcome substantial tension exerted on the shuttle thread. As the loop of needle thread continues to be pulled down towards the work by the take-up device, the bobbin 60

moves still further downwardly and pays off still more of the thread drawn off the bobbin after the conclusion of the last stitch setting operation until when the loop of needle thread is actually 5 pulling the shuttle thread against the work to lay it on the latter practically the whole amount of the thread pulled off the bobbin after the conclusion of the last stitch setting operation will have been paid out and the thread passing from 10 the shuttle to the work will be relatively slack. Therefore as the needle thread continues to lay the shuttle thread on to the work, which action takes place as the work is being fed towards the shuttle by work clamping members of the 15 machine, the slackened shuttle thread falls into a condition in which it can be easily laid against the work without exercising any substantial tension on the needle thread and without causing any appreciable reeling of the two threads together. The amount of thread pulled off the 20 bobbin and paid out by the rising and falling bobbin is of such a length (i. e. is three sixteenths of an inch long as previously indicated) that when sewing stitches of average length, all 25 the slackness thrown into the shuttle thread in a single cycle will have been used up in a single stitch formation or in stitch setting by the end of the stitch setting operation.

It will therefore be appreciated that by arranging for the shuttle thread to become slackened as it is engaged by the needle thread and pulled down on to the work very small resistance will be offered by the shuttle thread to being laid on the work, thus making for good stitch-making 30 and avoiding uneven setting of the thread locks within the work.

Immediately after a setting of a stitch is completed the bobbin case will, as above described, commence to rise to pull off thread from the 35 bobbin for the formation of the next stitch.

In the machine disclosed in prior application No. 688,480 the shuttle is arranged to be rotated by a spiral gear loosely mounted on a vertical rotating shaft and arranged to be coupled to the 40 shaft by a pair of spring pressed plungers mounted in a cam-member rigidly secured to the upper end of the shaft, conical lower ends of which spring pressed plungers engage in depressions in the upper face of the spiral gear. Such an arrangement was intended to couple the spiral gear 45 normally to the shaft so that the gear rotates with the shaft but to allow the gear to remain stationary if for any reason rotation of the shuttle should be obstructed. This arrangement, while satisfactory 50 when the machine runs at a moderate speed, has been found at a relatively high speed, not to provide as reliable a driving connection between the gear and shaft as is desired and accordingly in the illustrative embodiment now being described, four spring-pressed plungers 55 (Figures 8 and 11) are provided in the said cam member 17 the lower ends of which are bevelled to provide chisel-like ends 19, the lengths of which lie radially of the vertical shaft. A ring 21 secured 60 to the upper face of the said spiral gear, shown at 23, which rotates the shuttle, has four grooves 25 formed radially in it which are arranged at right angles to each other and the sides of which are bevelled similarly to the bevelled lower ends 65 19 of the plungers 15 which are arranged to engage within them. Since in the present illustrative embodiment four spring-pressed plungers 15 having chisel shaped lower ends are arranged to couple the gear 23 to the vertical shaft 70 75 27 a more positive driving connection between

the gear and this shaft is obtained thereby guarding effectively against relative slip occurring between the gear and the shaft during the normal operation of the machine while still allowing the shaft to rotate relatively to the said gear if the 5 shuttle should at any time become jammed against rotation. Relatively strong springs 29 are provided above the spring pressed plungers 15 to maintain their lower ends pressed firmly in the grooves in the ring secured to the said spiral gear. 10 As before stated, the shuttle is rotated twice in each cycle of the machine and it is necessary, in order that the correct timing of the shuttle in the machine shall be regained if relative slip has occurred for any reason between the spiral gear 15 and the vertical shaft, that the said gear should be prevented from once more becoming automatically coupled to the shaft by the said plungers until each plunger once more comes into line with the same groove in the ring secured to the 20 spiral gear as it engaged before the slip between the vertical shaft and the spiral gear occurred or until it comes into line with a groove lying diametrically opposite said groove. In order to ensure that the gear 23 will become coupled to the 25 shaft 27 only in one or other of these two positions, two lugs 31 are formed on the outer edge of said ring 21 and lie at the outer ends of two of the grooves which lie diametrically opposite each other and two similar lugs 33 are formed 30 on the inner edge of the ring 21 and lie at the inner ends of the other two grooves. Each of the two plungers which engage in the two grooves first above mentioned has an enlargement 35 formed on that side of its lower bevelled end 35 which lies nearer the axis of the said vertical shaft and each of the other two plungers which engage in the two grooves last above mentioned has an enlargement 37 formed on that side of its lower bevelled end which lies further from the 40 axis of the vertical shaft. The arrangement is such that if relative slip has occurred between the rotary shaft 27 and the said gear 23, the lugs 33 formed on the inner edge of the said ring will prevent the plungers 15, which have enlargements 45 35 formed on their lower ends nearer to the axis of the vertical shaft from entering the grooves adjacent these lugs but will allow those plungers having enlargements 37 formed on the outer sides of their lower ends to enter the said grooves. 50 Similarly the lugs 31 formed on the outer edge of the ring 21 while allowing those plungers which have enlargements 35 formed on the inner sides of their lower ends to enter the grooves will nevertheless prevent the plungers which have enlargements 37 formed on their outer sides from entering the grooves adjacent them. (As shown in 55 Figures 10 and 11.)

The illustrative embodiment is, like the machine disclosed in application No. 688,480 provided with 60 two thread locking devices arranged one to grip the needle thread between the supply and a thread measuring device or pull-off and the other between the thread measuring device and the stitch forming instrumentalities. Unlike the thread 65 locking devices of that machine, however, the thread locking devices of the present illustrative machine are arranged to be actuated independently through separate cam members and both devices are arranged simultaneously to be in gripping engagement with the needle thread over appreciable portions of the machine cycle. The thread locking devices of the present illustrative embodiment are like the devices of the machine 70 disclosed in the prior specification last referred 75

to, in that that one (hereinafter termed the lower or rear thread lock) which engages the needle thread between the supply and the thread measuring device comprises a relatively fixed 5 thread-engaging plate 41 (Figure 4) against which the thread is clamped by a cooperating plate 43 which is moved yieldingly horizontally towards it and the other locking device (hereinafter termed the upper or front thread lock) 10 which engages the thread between the thread measuring device and the stitch forming instrumentalities comprises a relatively fixed roll 45 over which the thread passes and a thread-engaging shoe 47 which is arranged to be lowered 15 towards the roll to press the thread against the upper face of the roll. In the present illustrative embodiment, however, two separate cam grooves are provided in a cam member 49 which is secured to a driving sleeve for the rotary take-up 20 device aforementioned and one of these cam grooves actuates a cam lever 51 which is coupled to the upper thread lock and the other cam groove actuates a second cam lever 53 which is coupled to the lower thread lock, the connections 25 from the two cam levers to their respective thread locks being separate and unconnected so that the two locks are operated independently of each other. The movable member of each of the thread locks is moved yieldingly to grip the thread at 30 certain times in the machine cycle against its cooperating stationary member through a spring plunger arrangement 55 included in the connections which connect it to its actuating cam lever but the movable members are arranged to be 35 moved out of engagement with the thread at the appropriate times in the machine cycle by a pin and slot connection 57 with the spring plunger which, when the spring behind the plunger has expanded to its original condition after the pressure of the movable member of the thread lock 40 on the thread has been released, causes the movable member to move positively somewhat away from its cooperating fixed member, thus ensuring that actual separation of the cooperating 45 members occurs at the desired times in the machine cycle. In the case of the lower lock, however, the movable member may be moved positively, i. e. unyieldingly, by its actuating mechanism and its cooperating relatively fixed member 50 may yield against a spring as the movable member presses the thread against it. Such an arrangement tends to minimize the hammering action which the movable member exerts on the thread as it moves rapidly to grip the thread. 55 The separate actuating mechanism for the upper and lower thread locks are arranged to act in such time relation relatively to each other and to the operation of the stitch forming instrumentalities of the machine that not only do both 60 thread locks grip the thread simultaneously throughout relatively long portions of the machine cycle during which there is a danger that thread might steal through the locks but also each lock, considered separately, is caused to engage the thread at especially convenient times in a cycle of the machine.

The particular times in the machine cycle at which the two locks grip and release the needle thread independently will now be indicated. In 70 the description which follows, it will be assumed that the stitch forming instrumentalities (with the exception of the shuttle which functions as above described) and the work feeding instrumentalities function and cooperate in the manner disclosed in the prior specification last mentioned.

Referring to Figures 12 to 23 and assuming the machine to be in operation sewing an outsole to a shoe and the stitch forming instrumentalities to have reached the positions they occupied when the machine was at rest, the take-up roll 42 of the rotary take-up device will be commencing to set the thread lock of the stitch last formed within the work. At this time the lower thread lock is in gripping engagement with the needle thread, the upper thread lock being open at this 10 time but being ready to close. During the next few degrees of rotation of the main shaft (e. g. during about twenty degrees of rotation of the main shaft from its stopping position) the take-up roll will have imparted the maximum tension 15 to the needle thread stretching the latter somewhat during the final setting of the stitch and the upper thread lock will have been closed and will have firmly gripped the thread, the bottom lock still remaining closed. The take-up roll will 20 have imparted the maximum tension to the thread only just before the upper lock is firmly closed upon the thread and will preferably commence to rise towards the work to pay out thread ready for the formation of the next stitch only 25 after the upper lock actually has closed. The fact that the take-up roll will have imparted the maximum tension to the thread and will have stretched the thread before the upper lock closes 30 would give rise to the danger that when the 35 take-up roll moves towards the work after having tensioned the thread, the tensioned thread, which will not instantaneously recover its unstretched condition, would, if the upper lock were open at that time, steal back somewhat through the top lock thus rendering the next thread measuring operation inaccurate and producing inaccurate setting of the next thread lock within the work. Since, however, the upper thread lock in the present illustrative embodiment is caused 40 to grip the thread almost immediately after the take-up roll has imparted the maximum tension to the needle thread, the danger of thread stealing back through the upper lock as the take-up roll rises towards the work is either obviated 45 or at least very substantially minimized. Since there is substantially no movement of the thread over the stationary roll of the upper lock taking place when the upper lock closes, there is no danger that reeling of the thread through the 50 lock will take place at that time. The upper lock grips the thread so soon after the take-up roll has imparted the maximum tension to it that it grips the thread while a considerable portion of this tension still remains in the thread 55 and therefore the portion of needle thread extending between the upper and lower locks is taut when the upper lock grips the thread.

Both the upper and lower locks remain gripping the thread simultaneously until, when the 60 take-up roll has risen somewhat towards the work and the machine shaft has rotated through about a hundred degrees from its stopping position the thread measuring device, which comprises a roll indicated at 44 and which is constructed, arranged and actuated as in the machine of application Serial No. 688,480, is ready to draw off from the supply the necessary amount of needle thread for the formation of the next 70 stitch. The lower lock there upon opens, while the upper lock remains gripped on the thread, and remains open while the main shaft of the machine rotates through about a further hundred and thirty degrees, during which time the thread measuring device operates to pull the 75

necessary amount of thread from the supply through the open bottom lock. Just about this time the shuttle beak enters the loop of needle thread pulled up through the work by the needle, 5 this pulling up of the needle loop being allowed by reason of the rising of the take-up roll while the upperlock still remains closed. Immediately after the thread-measuring device has completed its thread pulling off movement (i. e. when 10 the main shaft has rotated through two hundred and thirty degrees approximately) the lower lock closes and the thread pulled off the supply by the measuring device remains locked between the upper and lower thread locking devices. Both 15 the upper and lower locks remain simultaneously gripping the thread until the main shaft has rotated through about three hundred degrees, the loop of needle thread actually passing over the highest part of the shuttle when the main 20 shaft has rotated through about two hundred and eighty five degrees at which time the thread pulled off from the supply by the measuring device still remains locked between the upper and lower thread locks. When the main shaft has 25 rotated through about three hundred degrees the loop of needle thread has already passed over the highest part of the shuttle and is being pulled down by the take-up device and the upper lock then becomes unlocked while the lower lock still 30 remains gripped upon the thread. The lower lock remains in gripping engagement with the needle thread throughout the remainder of the cycle and until, in the next cycle, just before the thread measuring device operates once more 35 to draw off thread from the supply.

From the description above given of the relative times in the machine cycle at which the upper and lower thread locks are respectively closed and opened, it will be seen that between the time 40 when the take-up roll imparts the maximum tension to the thread and the time when the thread measuring device commences to pull off needle thread from the supply, both the upper and lower locks remain in gripping engagement with the 45 needle thread during a rotation of the main shaft through about eighty degrees. It will further be seen that during the period of time that elapses after the thread measuring device has pulled off the necessary amount of thread from the supply 50 but before the take-up roll imparts the maximum tension to the thread, both locks will remain in gripping engagement with the thread during about a rotation of the main shaft through about sixty-five degrees. Since the lower lock does not 55 close until after the thread measuring device has concluded its thread-pulling off function, at which time the upper lock is closed, no movement of the thread through the lower lock is taking place as the lower lock closes and therefore ob- 60 jectionable reeving of the thread through the closing lock is obviated. Since the two locks are simultaneously in gripping engagement with the thread throughout relatively large portions of the cycle each lock will have ample time to settle itself firmly on the thread before the other lock opens. 65

It will be appreciated that if the movable members of the upper and lower locks were always moved towards their cooperating stationary members to grip the thread between them from constant positions away from the stationary members whatever the thickness of the needle thread 70 not only would the intensity of the gripping action of the locks on the thread vary with threads of different thicknesses but also the space provided between the movable and stationary mem-

bers of the locks when the latter are open would be greater than is necessary when the needle thread is a relatively fine one and might be less than is desirable when the needle thread is a relatively thick one. In order that a uniform 5 clearance may be provided between the thread, whatever the thickness of the latter, and the thread engaging members of the locks when the latter are open and also in order that the precise times in the machine cycle at which the locks 10 actually grip the thread may be the same for all thicknesses of thread, an eccentric setting is provided for the movable member of each lock by adjustment of which the position from which the movable member starts to move towards its co- 15 operating stationary member can be adjusted without disturbing the times at which the movable member is actuated by its operating mechanism.

The eccentric setting for the upper thread lock 20 comprises a sleeve 59 rotatably mounted in a bearing in a bracket 61. The sleeve 59 has eccentrically mounted in it a spindle 63 rotation of which moves the thread-engaging shoe 47 towards or from the fixed roll 45. The sleeve 59 25 has extending from it an arm 65 having formed in it a slot 67 through which passes a screw 69 threaded into the bracket 61. When the screw 69 is slackened, the sleeve 59 may be rotated by means of the arm 65 to adjust the shoe 47 towards 30 or from the roll 45. The eccentric setting of the lower thread lock comprises a stud 71 which is secured in the cam lever 53 and having an eccentric portion 73 on which is mounted a cam roll 75 35 engaging in one of the cam grooves in the cam block 49. By rotating the stud 71, the plate 43 may be adjusted towards or from the plate 41.

As in the case of the machine disclosed in prior application No. 688,480, the machine of the illustrative embodiment comes to a stop while the lower thread lock is closed upon the thread and mechanism connected to the stop motion of the machine and similar to that described in that application is embodied in the machine of the present illustrative embodiment to open the lower 45 thread lock when the machine stops to allow the operator to draw through it in removing the work from the machine. The said mechanism comprises an eccentric sleeve 77 on which the cam lever 53 is pivoted. The sleeve 77 is pivoted on 50 a pin 79 secured in bearings 81, 81 extending from the bracket 61 and has extending from it an arm 83 which is connected by a pin and slot connection to a rod 85. The rod 85 is connected to a bell-crank lever 87 which is connected by a rod 89 to the said stop motion of the machine. The sleeve 77 also has extending from it an arm 91 to which is connected one end of a spring 93 the other end of which is connected to the machine frame. When the clutch controlling treadle of the machine is depressed to start the machine, the spring 93 is allowed to swing the eccentric sleeve 77 in an anti-clockwise direction, as viewed in Figure 4, until the arm 83 engages a plate 95 65 secured on one of the bearings 81. Movement of the eccentric sleeve 77 in this direction swings the cam lever 53 about the axis of the cam roll 75 and moves the plate 43 towards the plate 41 70 into a position from which it can be moved by the cam lever 53 when it is actuated by its cam at the appropriate time in the machine cycle towards the plate 41 to grip the thread. As the machine comes to rest, the eccentric sleeve 77 is 75 swung in the opposite direction and causes the

plate 43 to be moved away from the plate 41 to release the thread.

Since the upper thread lock is actuated independently of the lower lock, it may, if desired, be arranged to grip the thread somewhat earlier in the machine cycle than above set forth in order that the upper and lower thread locks may both be gripping the thread just previous to and during the time that the take-up device is imparting the maximum tension to the needle thread during the setting of the stitch so that greater resistance to drawing of the thread through the locks at this time may be secured. If, however, the upper lock is arranged to grip the needle thread some little time before the take-up device imparts the maximum stretch setting tension to the needle thread, it will happen that when the machine comes to a stop not only will the lower lock be gripping the thread, but the upper lock will also be gripping the thread and consequently it will be necessary to include in the machine mechanism which may be similar to that for opening the lower lock when the machine stops, for opening also the upper lock at this time.

The nature and scope of the invention having been indicated, and a machine embodying the several features of the invention having been specifically described, what is claimed is:

1. A lockstitch sewing machine having, in combination, stitch forming devices comprising a needle, a shuttle, a take-up, a pull-off, a front thread lock between the take-up and pull-off, a rear thread lock between the pull-off and the supply, and means for actuating the parts to cause the take-up to set the stitch while the rear thread lock is closed and to close the front thread lock while the thread is being strained by the take-up.

2. A lockstitch sewing machine having, in combination, stitch forming devices comprising a needle, a shuttle, a take-up, a pull-off, a front thread lock between the take-up and pull-off, a rear thread lock between the pull-off and the supply, and means for actuating the parts to cause the pull-off to pull thread from the supply while the front thread lock is closed and while the rear thread lock is open, and to maintain the front thread lock closed until the needle loop passes over the top of the shuttle.

3. A lockstitch sewing machine having, in combination, stitch forming devices comprising a needle, a shuttle, a take-up, a pull-off, a front thread lock between the take-up and pull-off, a rear thread lock between the pull-off and the supply, and means for actuating the parts to cause the take-up to set the stitch while the rear thread lock is closed, to close the front thread lock while the thread is being strained by the take-up, to cause the pull-off to pull thread from the supply while the front thread lock is closed and while the rear thread lock is open, and to maintain the front thread lock closed until the needle loop passes over the top of the shuttle.

4. A lockstitch sewing machine having, in combination, stitch forming devices comprising a needle, a shuttle, a take-up, a pull-off, a front thread lock between the take-up and pull-off, a rear thread lock between the pull-off and the supply, and means for actuating the parts to cause the take-up to set the stitch while the rear lock is closed and while the front lock is open and to cause the pull-off to pull thread from the supply while the front lock is closed and while the rear lock is open, and means for varying the

time during the stitch forming cycle at which the locks are actuated.

5. A lockstitch sewing machine having, in combination, stitch forming devices comprising a hook needle, a discoidal shuttle having a loop taking beak and a thread case mounted in the shuttle provided with an opening for the passage of the shuttle thread from the thread case to the work and formed with a radially projecting nose extending beyond the thread opening into a position to hold the shuttle thread out of the path of the shuttle beak.

6. A lockstitch sewing machine having, in combination, stitch forming devices comprising a needle, a shaft making one rotation during each stitch forming cycle, a gear on the shaft, a rotary shuttle driven from said gear and a slip driving connection between the gear and the shaft comprising a plurality of spring plungers mounted on the shaft and provided with chisel-like ends engaging radial grooves in the gear.

7. A lockstitch sewing machine having, in combination, stitch forming devices comprising a needle, a shaft making one rotation during each stitch forming cycle, a gear on the shaft, a multiple rotary shuttle driven from said gear, a slip driving connection between the gear and the shaft comprising a plurality of spring plungers mounted on the shaft and arranged to engage at their ends with equally spaced recesses in the gear, and means acting during the relative rotary movement of the shaft and gear to permit engagement of each plunger with a portion only of said recesses.

8. A lockstitch sewing machine having, in combination, stitch forming devices comprising a needle, a shaft making one rotation during each stitch forming cycle, a gear on the shaft, a two-to-one rotary shuttle driven from said gear, a slip driving connection between the gear and the shaft comprising four spring plungers mounted on the shaft and provided with chisel-like ends engaging equally spaced radial grooves on the gear, and means acting during a relative rotary movement of the shaft and gear to permit engagement of each plunger with diametrically opposite grooves only.

9. A lockstitch sewing machine having, in combination, stitch forming devices comprising a needle, a shaft making one rotation during each stitch forming cycle, a gear on the shaft, a multiple rotary shuttle driven from said gear, a slip driving connection between the gear and the shaft comprising a plurality of spring pressed plungers mounted on the shaft and arranged to engage at their ends with recesses in the gear, and lugs on the shaft cooperating with the plungers during a relative rotary movement of the shaft and gear to permit engagement of each plunger with a portion only of said recesses.

10. A lockstitch sewing machine having, in combination, stitch forming devices comprising a hooked needle, a take-up acting during each stitch forming cycle to pull a loop of needle thread from the shuttle and set the stitch, a rotating discoidal shuttle, means actuated by the rotation of the shuttle to pull off and give up shuttle thread, and means for rotating the shuttle in timed relation to the take-up to cause thread to be pulled from the shuttle after a stitch has been set by the take-up and while tension is being exerted on the set stitch by the take-up and to give up thread while the next needle loop is being drawn from the shuttle into the work by the take-up.

11. A lockstitch sewing machine having in combination, stitch forming devices comprising a hooked needle, a take-up acting during each stitch forming cycle to pull a loop of needle thread from the shuttle and set the stitch, a rotating discoidal shuttle, a non-rotating bobbin case mounted eccentrically in the shuttle acting to pull off and give up shuttle thread during the rotation of the shuttle, and means for rotating the shuttle in timed relation to the take-up to cause thread to be pulled from the shuttle after a stitch has been set by the take-up and while tension is being exerted on the set stitch by the take-up and to give up thread while the next needle loop is being drawn from the shuttle into the work by the take-up.
12. A lockstitch sewing machine having, in combination, stitch forming devices comprising a hooked needle, a take-up, a rotating discoidal shuttle, means for imparting a plurality of rotations to the shuttle during each stitch forming cycle, and means actuated by the shuttle during one rotation to pull thread from the shuttle after a stitch has been set by the take-up

and while tension is being exerted on the set stitch by the take-up and during a subsequent rotation of the shuttle to give up thread while the next needle loop is being drawn from the shuttle into the work by the take-up.

5

13. A lockstitch sewing machine having, in combination, stitch forming devices comprising a hooked needle, a take-up, a rotating discoidal shuttle, a non-rotating bobbin case mounted eccentrically in the shuttle acting to pull off and give up thread, and means for imparting a plurality of rotations to the shuttle during each stitch forming cycle in timed relation to the take-up to cause thread to be pulled from the shuttle during one rotation after a stitch has been set by the take-up and while tension is being exerted on a set stitch by the take-up and to give up thread during a subsequent rotation of the shuttle while the next needle loop is being drawn from the shuttle into the work by the take-up.
